INVENTOR

BY *Victor J. Evans*

ATTORNEY

WITNESS:

UNITED STATES PATENT OFFICE.

TORGER A. BAKKETUN, OF NORTHWOOD, IOWA.

GAME.

Application filed April 12, 1923. Serial No. 631,641.

To all whom it may concern:

Be it known that I, TORGER A. BAKKETUN, a citizen of the United States, residing at Northwood, in the county of Worth and

5 State of Iowa, have invented new and useful Improvements in Games, of which the following is a specification.

This invention relates to amusement devices, particularly to games, and has for its 10 object the provision of a game consisting of a playing surface formed with a circular series of depressions, the device further including a rotary spinner member located at the center of the playing surface for knocking a plurality of balls over the playing surface, the balls being received within said depressions, the playing surface being inscribed near the depressions with various 15 indicia by means of which a numerical score may be obtained, a dice game may be played or fortunes may be told, in addition to spelling out the answers to questions.

An important object is the provision of a 20 game of this character which is entertaining and amusing to persons of all ages and which may moreover be so constructed, decorated and arranged as to have a mystic appearance and atmosphere which will heighten the attractiveness.

30 An additional object is the provision of a game of this character which will be simple and inexpensive to manufacture, easy to play, efficient and durable in service and a general improvement in the art.

35 With the above and other objects and advantages in view the invention consists in the details of construction to be hereinafter more fully described and claimed and illustrated in the accompanying drawings, in 40 which:

Figure 1 is a plan view of the device,

Figure 2 is a bottom plan view,

Figure 3 is a cross section,

45 Figure 4 is an enlarged detail view of a portion of the playing surface showing the various indicia thereon in greater detail.

Referring more particularly to the drawings I have shown my device as comprising a board or other surface 10 which is dished 50 so that the center will be the lowest point. Secured to the edges of this board are side members 11 which give the device a box like appearance and which rest upon a table top or the like for supporting the device in playing position. Secured to the side members is the top 12 which is formed with a circu-

lar opening 13 of less diameter than the playing surface so as to define an overhanging flange 14. Extending across the corners between the board 10 and top 12 are diagonal strips 13'.

The playing surface of the board is divided by radial lines 16 inscribed thereon into a plurality of segments 17 and located in these segments is a circular series of depressions or recesses 18 formed in the playing surface. Adjacent the recesses are various indicia to be used in the actual playing of the game, and in the indicia I have illustrated series of letters of the alphabet, numbers, arbitrary symbols, having a secret meaning in accordance with the rules of the game, and also the representation of ordinary playing dice.

Secured upon the underside of the board 75 10 are depending brackets 19 arranged in crossed relation and forming a bearing for the lower end of a shaft 20 which is journaled through the board and which carries a heavy fly wheel 21 rotatable within 80 the confines of the brackets. Above the board this shaft carries a turning member 22 and a plurality of radial arms 23. In the present instance the turning member is represented as the head of an oriental or other 85 person, though this detail is simply for ornamental purposes and to correspond with the entire decorative scheme which may be applied to the playing surface and to the top 12. As much or as little ornamentation 90 may be used as preferred depending upon the taste of the individual manufacturer and the intended cost of production. In conjunction with the playing surface and the turning member, I make use of a plurality 95 of balls 24, preferably 13 in number, though of course some other number might be used to equal advantage.

In playing the game the operator grasps 100 the member 22 between his thumb and forefinger and spins it whereupon the fly wheel 21 will be set in motion. Owing to the momentum of the fly wheel it is apparent that the turning member or radial arms or "kickers" carried thereby will rotate for 105 a considerable period of time. The balls 24 may be initially placed upon the playing surface prior to the spinning of the turning member or they may be dropped upon the board after the turning member is set in motion, this detail not effecting the operation. As the arms 23 rotate they will of 110

course knock against the balls 24 and force them along and upon the playing surface along different lines. The balls will naturally drop into the recesses 18 eventually though of course it is conceivable that some of the balls may not do so. The element of chance thus enters into the playing of the game. For use by children it is intended primarily that the numerical indicia be used and that the numbers adjacent the recesses occupied by the different balls be added together for ascertaining the score. In case the device is used for ascertaining fortuitous answers to questions which may be secretly written in advance or which may be propounded orally, the letter indicia are used, the letters adjacent the occupied recesses being placed together to form words in answer to the question. The device may also be used in playing different games of dice, the dice indicia in this instance being used instead of the others, and it being preferable in such case that a small number of balls be employed. The device is also well adapted for telling fortunes by observing the various secret symbols adjacent the occupied recesses and noting the number of times the symbol occurs as the result of the play of each player. All the details of the possibility of playing are not necessary to be explained as the adaptability and capabilities of the device will be readily apparent to a person of imagination. From the foregoing description and a study of the drawings it will be apparent that I have thus provided a simple game device which will be extremely attractive, interesting, entertaining, amusing even to the adult, and instructive to children. Owing to the simplicity of the construction and

the fewness of the parts it is apparent that there is little to get out of order so that the device should have a long life and satisfactorily perform all of its functions.

While I have shown and described the preferred embodiment of the invention it is of course to be understood that I reserve the right to make such changes in the form, construction and arrangement of parts as will not depart from the spirit of the invention or the scope of the subjoined claim.

Having thus described my invention I claim:

A game device comprising a board dished toward its center, and having secured to its edges side members which rest upon a supporting surface to elevate the board and present a box-like appearance, a top secured to the side members and formed with a circular opening of less diameter than the playing surface of the board, thereby defining an overhanging flange, a series of recesses formed in the playing surface, the playing surface being inscribed with various indicia, depending brackets in crossed relation secured to the underside of the board, a shaft having a bearing in said brackets and passed through the board at its lowest point, a fly wheel mounted on the shaft between the brackets and the underside of the board, a flat head rigid on the upper end of the shaft for turning the same, and a plurality of radial arms formed at the base of the head and resting flat on the board, in combination with a plurality of balls disposed on said playing surface and adapted to be engaged by said arms.

In testimony whereof I affix my signature.

TORGER A. BAKKETUN.
